F. W. Coy,

Carpenter's Gage.

U. S. 78,065. Patented May 19, 1868.

FIG. 2.

FIG. 1.

A. Van Berry

Inventor:

J. W. Coy

United States Patent Office.

F. W. COY, OF BOSTON, MASSACHUSETTS.

Letters Patent No. 78,065, dated May 19, 1868.

IMPROVEMENT IN CARPENTERS' GAUGES.

The Schedule referred to in these Letters Patent and making part of the same.

TO ALL WHOM IT MAY CONCERN:

Be it known that I, F. W. Coy, of Boston, in the county of Suffolk, and State of Massachusetts, have invented certain new and useful Improvements in Carpenters' Gauges; and I do hereby declare that the following is a full and exact description thereof, reference being had to the accompanying drawings, and to the letters of reference marked thereon.

The nature of my invention consists in so arranging the head of a carpenter's gauge that that part of it which forms the guide may be set at any desired angle, so as to fit the bevel of the stock being worked.

To enable others skilled in the art to make and use my invention, I will proceed to describe its construction and use.

In the drawings—

Figure 1 is a view in elevation, showing the gauge complete.

Figure 2 is a view of the adjustable guide.

The beam or rule A B is made of wood or any suitable material, and in the usual manner. Sliding upon this block is the guide-carrier C, which is provided with a set-screw, D, so that it may be made fast at any point on the beam A B.

If desirable, the guide-carrier may be moved along the beam by a longitudinal screw passing through the beam, and connected to the carrier by a screw-nut. Among mechanics this device is called a "tail-screw." The adjustable guide H L is so attached to the carrier that it is free to swing on the point S, as indicated by the dotted lines in fig. 1, and may be held at any desired angle by the set-screw K.

By loosening the set-screw K, the guide H L may be turned so that the plane L may form any angle with the beam A B, thus adapting the gauge to work bevelled stock.

Having thus described my invention, I will proceed to set forth my claim.

What I claim as my invention, and desire to secure by Letters Patent, is—

A carpenters' gauge, the guide L of which is capable of angular adjustment, in the manner and operating substantially as described and for the purpose set forth.
